UNITED STATES PATENT OFFICE.

DANIEL T. FELLENBAUM, OF COATESVILLE, PENNSYLVANIA.

MILK-CAN RACK.

Application filed September 10, 1926. Serial No. 134,685.

This invention relates to an improved rack which is especially, but not necessarily, adapted for use on a dairy farm or the like for supporting a plurality of milk cans.

5 Briefly, the invention has more particular reference to a supporting frame for a sheet metal shed, together with one or more rockably mounted supporting frames designed to hold a plurality of milk cans in 10 level or tilted position, whereby to permit the same to be readily sterilized, cleaned, and dried.

More in detail, the invention has reference to an open front metallic shed containing superposed rockably mounted can-supporting frames, together with manually operated levers for moving the frames to different positions, whereby to permit the cans to be tilted downwardly for draining, and 20 to be arranged on a substantially horizontal level for filling and cleaning or to be swung upwardly to permit entrance of sun-rays to be utilized in drying.

Other features and advantages of the invention will become apparent from the following description and drawings.

In the drawings:—

Figure 1 is a front elevation of a structure constructed in accordance with the invention,

Fig. 2 is a horizontal section through the same,

Fig. 3 is a view looking at one end of the structure, and

Fig. 4 is a vertical transverse section looking at the interior of the opposite end of the structure.

In the drawings reference character 1 designates generally the open front metallic shed which includes a skeleton frame-work supporting structure represented generally by the reference character 2. This frame-work embodies a plurality of vertical angle-irons 3 connected to a top frame composed of additional angle-irons 4. The angle-irons 4 are connected together by horizontal cross members 5. These cross members constitute supporting means for the swingably mounted racks 6. Secured to the frame-work are corrugated sheets of metal 7, there being two end sheets, one back sheet, and a top sheet, forming the aforesaid open front housing or shed. By preference, the roof is downwardly inclined to cast off water. On the interior and beneath this

roof is a supporting shelf 8 for various small articles such as can tops, strainers, and the like. This is clearly shown in Fig. 1 and it will also be seen from this figure that diagonal cross pieces 9 are employed 60 to secure rigidity of construction.

Each rack is in the form of a swingably mounted frame comprising a pair of end members 10, longitudinal members 11, connections 12 between said members 10 and 11, 65 and a rod member 13. The member 13 is bent at longitudinally spaced points as at 14 to provide seats for reception of the necks of the milk-cans 15 represented in dotted lines. The members 10 and 11 are in the form of 70 angle irons and it will be noted that the member 11 is adjustable through the medium of the brackets 12 along the members 10 to permit the size of the supporting rack to be varied according to the size of the cans 75 which are to be supported thereon. The member 11 also constitutes a supporting ledge for the bottom portion of the can while the opposite end neck portions are supported in the aforesaid seats 14. In this way slip-page of the cans either forwardly or rearwardly is prevented even though they may be tilted downwardly or upwardly. Each rack is provided with a rigidly mounted 80 hand lever 15 engageable with notches 16 in 85 one of the vertical angle bars, whereby the rack may be held in a level position, in a horizontal plane or in upwardly or downwardly tilted position.

By disposing the can racks in a horizontal 90 plane, the cans may be readily steamed and cleaned, after which the racks may be tilted downwardly to allow the cans to be drained. Then after this, the racks may be tilted in a manner to dispose the open ends of the 95 cans upwardly, as shown in Fig. 1, whereby to permit sun rays to enter the cans for drying. Later, the cans can be rinsed with clear water for cooling before filling with milk. With this arrangement it will be seen that I 100 have evolved and produced a very novel housing which may be employed in a sanitary manner for cleaning and simultaneously handling a number of milk cans. The practicability and simplicity, together with the 105 compactness and convenience of arrangement of the parts is quite clear, and it is also obvious that the cost of the manufacture and maintenance of such a structure is quite negligible.

It is believed that by considering the description in connection with the drawings, a clear understanding of the invention will be had. Therefore, a more lengthy description is thought unnecessary.

Minor changes coming within the field of invention claimed may be resorted to if desired.

I claim:—

- 10 1. In a structure of the class described, a housing, a rockably mounted frame mounted in said housing and constructed for supporting a plurality of milk cans, and an operating lever carried by said frame, said housing including keeper seats for reception of

said lever for holding said frame in various adjusted positions.

2. In a structure of the class described, including a supporting frame, a milk can rack pivotally mounted upon a horizontal axis on said frame, said rack embodying end bars, a longitudinal bar between said end bars, said longitudinal bar being of angular cross-section, and a rod disposed between the opposite ends of said end bars, said rod being bent at longitudinally spaced points to provide can neck seats, and operating and retaining means for said rack.

In testimony whereof I affix my signature.

DANIEL T. FELLENBAUM.
